TIE AND BELT HANGER

Paul F. Bertram, St. Louis, Mo., assignor to Lee-Rowan Company, St. Louis, Mo., a corporation of Missouri

Filed Aug. 28, 1963, Ser. No. 76,375

Term of patent 14 years

(Cl. D80—8)

I claim:

The ornamental design for a tie and belt hanger, substantially as shown.
